EARL J. W. RAGSDALE, OF NORRISTOWN, PENNSYLVANIA, ASSIGNOR TO EDWARD G. BUDD
MANUFACTURING COMPANY, OF PHILADELPHIA, PENNSYLVANIA, A CORPORATION
OF PENNSYLVANIA

LIGHT METALLIC TRUSS STRUCTURE

Application filed May 29, 1930. Serial No. 456,993.

The invention relates to light metallic trussing, and particularly to trussing of this kind well adapted for use in aircraft construction, such as the ribs of airplane wings.

It is among the objects of my invention to construct such trussing in a manner that it can be very economically constructed and assembled, that it may be of very light weight, yet strong, durable and capable of 10 withstanding the fatiguing and bending draws to which such devices are subject.

These objects are in large part attained by making the web and chord members of thin gauge metal and which may be and 15 preferably is, non-rusting, such as one of the numerous stainless steel alloys and of such cross section as will permit them to be most readily and strongly joined together by that most economical of methods of joinder, 20 namely, spot welding.

Other and further objects and advantages will become apparent from the following detailed description in connection with the specific embodiment of the invention shown 25 in the accompanying drawing, forming a part of this specification.

In the drawing,

Fig. 1 is a side elevational view of an airplane rib constructed in accordance with the 30 invention.

Fig. 2 is a detail perspective view of one of the web members joining the chords.

Fig. 3 is a sectional view taken on the line 3-3 of Fig. 1.

Fig. 4 is a detail perspective of another form of web member adjacent the wing spar 35 location.

Fig. 5 is a sectional view taken on the line 5-5 of Fig. 1.

Fig. 6 is a detail perspective showing the 40 connection of the rear end of the chords.

Fig. 7 shows in perspective the gusset and nose piece joining the front ends of the chords.

According to the embodiment of the invention disclosed in the drawing, the upper chord 45 10 and the lower chord 11 are both formed of channel section, the channel facing each other and conforming in contour to the contour of the upper and lower wing surfaces.

The chords are joined by diagonal and ver-

tical web member 12, shown in detail in Figs. 2 and 3. These are generally of Z-section, the ends of the Z fitting within the channels of the chords and are secured to the side walls of the channel by spot welding. This Z-shape 55 of the web members make possible the dispensing with gussets while at the same time securing the advantage of the wide anchorage zone between chords and webs, which is obtained by the use of gussets. To further 60 strengthen and stiffen the web members between their ends, the edges of the webs of the Z are flanged laterally as at 13, thus forming with the web 14 of the Z the shallow opposite-facing channels, as clearly appears in 65 Fig. 3.

Adjacent the ends of the rib where the front and rear wing spars are attached to the rib, in place of Z-shaped webs, the angular section webs 15 may be used, one of which is 70 shown in detail in Figs. 4 and 5.

These webs are in general of channel section having their ends telescoped into the channels of the chords and secured thereto by spot welding. There are two such webs arranged in parallel relation to receive a spar between them, the bottoms of the channels of the webs presenting toward each other, and intermediate their ends on of the side walls of the channel, as 16, is preferably bent out into 80 the plane of the bottom to form a wide face for guiding and securing the rib to a spar.

At the rear ends, the chords 10 and 11 approach each other and their ends are arranged in telescoping relation, as shown in 85 Fig. 6, the side walls of the channels being secured together by spot welding.

At the front, the chords approach each other but terminate with their ends in spaced apart relation. The nose of the rib is formed 90 conveniently by a flat gusset member 17 having a strengthening rib, as 18, and a rear edge flange 19. The top and bottom edges of the gusset overlap and are joined to a side wall of the chord members by spot welding and the upper and lower edges of the gusset form a continuation of the curvature of the top and bottom chords until they merge in the apex. To receive an edge strip, not shown, the gusset is formed at its apex with a recess 20, 100

formed by slitting and bending the portion 21 between the slits laterally to serve as a tab for securing the edge strip in place.

While I have herein described a specific embodiment of my invention as applied to airplane ribs, it will be understood that I do not intend to be limited to the precise construction or application so described but only as required by the spirit and scope of the invention as expressed in the appended claims.

10 What I claim is:

1. In a light metallic truss member, opposed channel section chords joined together by generally Z-section web members having their opposite arms secured respectively to the opposite side walls of the channels.
2. A web member for light metallic truss structures of generally Z-section adjacent its ends, and having the arms of the Z intermediate its ends laterally flanged to form with the web of the Z, shallow oppositely facing channels.
3. In a light metallic truss structure, upper and lower chords, a gusset member joining the front ends of the chords to form a rounded apex, a part of said rounded apex of the member being bent laterally to provide a recess for receiving an edge strip.

25 In testimony whereof I hereunto affix my
30 signature.

EARL J. W. RAGSDALE.
